FRAME AND HANDLE ASSEMBLY FOR MIRRORS, BRUSHES, AND THE LIKE

William Steinen, South Orange, N. J.

Application February 26, 1938, Serial No. 192,690

8 Claims. (Cl. 88—102)

The present invention relates to a frame and handle assembly which may be utilized for mirrors, brushes and other utensils or devices to be utilized in connection with dresser sets.

5 It is among the objects of the present invention to provide an improved frame and handle assembly to be utilized for mirrors, brushes and the like which will be of few parts and of durable construction and which may be manufactured at 10 a minimum of expense.

Another object is to provide an improved mirror and brush assembly which may be of artistic durable and inexpensive construction, and which at the same time will omit any screw machine 15 parts and special metal elements which might unduly increase the expense of the assembly.

Another object is to provide an improved mirror and brush assembly in which the frame may be inexpensively constructed of sheet metal and 20 in which the backing or support plate may be made of a relatively stiff fibrous material, such as paper, and with assurance that the construction will be rigid and durable and may be subjected to rough usage over long periods of time 25 without tending to separate or become dismantled.

Other objects will be obvious or will appear during the course of the following specification.

In accomplishing the above objects, it has been 30 found most suitable to form a unitary frame construction of a flexible U-cross section strip of metal, which is designed to have frame portions forming a frame of round, oval or polygonal shape and which is designed to have two 35 continuing integral portions extending side by side to form the interior sides of the handle structure.

Enclosed between the U-shaped recesses of 40 the flexible member is a backing member having the same outline as the frame and handle, the periphery of which is to be inserted between and clamped between the side flanges of the 45 continuous U-shaped border strip.

One side of the backing member may be provided with an ornamentation either directly applied thereto or consisting of a separate celluloid or metal plate and at the other side of the 50 backing plate, there may be provided the mirror, brush back or other element which is clamped in the frame and which has the same contour as the frame portion of the backing member.

The handle portions of the backing member are preferably enclosed between sheet metal plates which flare up beyond the junction of the 55 frame and handle to reinforce such junction.

Desirably, these sheet metal plates for the handle are provided with embossments or abutments to receive or hold a locking ring which may be slid up upon the handle to lock the entire construction together.

The split ends of the flexible border member may be held together by a clip or lock at the bottom or end of the handle to form a rigid permanent connection.

If desired, in certain instances, the locking 10 band may also be held in position by embossments or notches on the sides of the channel members.

Ordinarily with a round or oval mirror, the 15 backing member need not be reenforced at the junction of the frame and handle, but with a square frame it is often desirable to attach an extra reinforcing strip which will extend across said junction and reinforce the back particularly when it is made of heavy paper stock.

The reinforcing strip may be clamped or 20 stapled onto the outside of the backing member or it may be inserted interiorly between the plies of the backing member.

It is also possible, in certain instances, in a 25 less preferred embodiment, to make the border U-shaped strip in two parts, the ends of which will interlock with one another inside of the locking band or sleeve at or adjacent to the junction 30 of the frame or the handle.

In such a case, it is usually desirable to have 35 the ends of the border U-shaped channel members fit inside of each other and to be locked to the sleeve and to the facing plates in the handle.

In the drawing which shows several of the 40 various embodiments of the present invention but to which the present invention is by no means restricted, the drawing being by way of illustration and not by way of limitation;

Figure 1 is an elevational view of a frame and handle assembly showing a mirror in position and with the locking band in place.

Figure 2 is an enlarged view of the junction 45 of the frame and handle before the locking band is inserted and upon an enlarged scale, as compared to Figure 1.

Figure 3 is a fragmentary elevational view 50 similar to Figure 2 showing the lock and band finally put in position.

Figures 4 and 5 are respectively transverse sectional views upon the lines 4—4 and 5—5 of Figures 2 and 3.

Figure 6 is an exploded view upon enlarged 55

scale of the bottom of the handle showing the locking clip removed.

Figure 7 is a similar view upon the same scale as Figure 6 showing the locking clip in position.

Figure 8 is a transverse sectional view upon enlarged scale as compared to Figure 7 upon the line 8-8 of Figure 7.

Figure 9 is an elevational view upon a small scale as compared to Figure 1, of an alternative backing construction showing a reenforcing strip in position thereon.

Figure 10 is a fragmentary sectional view showing an alternative construction in which the locking band is stepped and engages channel frame members which engage each other at the same time at the junction of the frame and handle portions with the backing member and the face plates for the handle removed.

Figure 11 is a transverse sectional view upon enlarged scale as compared to Fig. 1 upon the line 11-11 of Fig. 1.

Referring to Figure 1, there is provided an outside border frame A, a mirror B, which may be replaced by a brush back or other device, a backing plate C having a frame of the same contour as the mirror B and a handle extension, as indicated in Figures 4, 5 and 11, and the handle facing plates D, which are separate, it is obvious they could be made in the form of a flat tube into which the extension 30 may be inserted.

The present invention is particularly directed to the provision of a locking band F which draws up and tightens the entire assembly and replaces the usual threaded rod and nut construction widely employed.

This locking band F enables a much simpler, lighter weight, more artistic construction which is very durable and much less expensive than the constructions employing a central metallic rod welded or riveted to a backing plate and provided with a take up nut at the end of the handle construction.

Referring to Figure 1, the channel member is provided with a base 20, a front flange 21 and a back flange 22, between which flanges are clamped the bevel edge 23 of the mirror B, the frame portion 24 of the backing plate C and the ornamental back 25 of the backing plate 24.

It will be noted that the peripheral edges of the mirror B, the backing plate C and the ornamental back 25 all contact the bottom 20 of the channel member or rim A.

The channel member A is provided with the side portions 26, which, as shown in Figure 1, are shaped to form an oval or circular frame and which extend exteriorly around the mirror B and frame portion 24 of the backing structure C.

The channel member A has inwardly converging portions 27 which diagrammatically in un-tightened position take the location of the dotted lines 28, indicated in Figure 1.

These converging portions 27 terminate in the parallel portions or substantially parallel portions 29, which enclose and between which is clamped the facing plates D of the handle structure and also the extension 30 of the backing member C. The plates extend the full length of the handle, as does also the handle extension 30 of the backing member.

The upper ends of the plates D are flared as indicated at 31, to form a support at the junction of the frame and handle and also to limit the take up of the channel A from the dotted line positions 28.

As indicated best in Figures 4 and 5, the plates D have a stepped construction and the flanges 21

and 22 of the U-portions 29 abut at their side edges against the shoulders 32 and 33, of said plates D.

The ends of the plates are turned inwardly as indicated at 34 to abut the periphery 35 of the handle portion 30 and also to abut the base 20 of the channel portions 29.

It will be noted, by the construction shown in Figure 4, the flanges 21 and 22 are flush with the face of the intermediate stepped portions 36 of the plates D, which gives a much neater and more desirable construction.

Although, as shown, the facing plates D are separate, it is obvious they could be made in the form of a flat tube into which the extension 30 may be inserted.

The backing member C, as shown in the present application may be of heavy cardboard, but if desired, may also be made of metal and the handle portion 30 may extend partly or wholly into the handle between the plates D.

The lower end portions of the channel strip A are inturned, as indicated at 37 and they abut, as indicated at 38 and are provided with depressions or holes 39.

The clip E is provided with spaced indentations 40, corresponding to the holes or recesses 39 and has an ornamental lower edge 41, the inside portions 42 of which are designed to abut the base 20 of the channel portions 37.

When the depressions notch into the holes 39, the handle, as illustrated in Figures 1, 7 and 8 will be held firmly in position.

It will be noted that the outside edges 43 of said clip E are flush with the edges 44 of the channel portions and are also flush with the shoulders 32 and 33.

The locking band F may be placed upon the handle before or after the attachment of the clip E and may be forced up upon the handle until it snaps into the recesses 45, as best shown in Figure 2.

The recesses 45 are formed between the ends 46 of the central embossed band 47 in the manner indicated on Figure 3.

At the same time, the sides of the band are preferably indented, as indicated at 48, to fit into the recesses or holes 49 in the sides of the channel A, at the place of lodgment of the band F.

This will form a firm rigid construction and will tightly draw up the channel member A around the mirror B, the backing plate and the plates D.

The construction will be firm and rigid and most durable and of unusual thinness due to the absence of reenforcing metal rods extending through the handle construction.

In the backing plate construction of the type used in Figure 1, it is not necessary to use a reinforcement, but where the backing plate is of paper and the frame is square or rectangular, as indicated in Figure 9, it is often desirable to include a reenforcing strip 50 which is clipped or otherwise secured in position, as indicated at 51 and 52, but which may also be inserted, if desired, between the plies of the paper structure C.

In Figure 9, similarly functioning parts as those in the embodiment of Figures 1 to 8 are indicated by the same numerals primed.

In Figure 10, the locking band F² is shown as having a stepped construction with a wider portion 53 to receive the lower ends 54 of the frame elements 26² of the channel A².

The lower portion of the band F² is narrow, in-

dicated at 54A and receives the upper portions 55 of the handle sections 29².

As indicated, the bottoms of the portions 54 and 55 are provided with recesses 56 and 57 receiving the indented elements 58 and 59 from the sides of said locking band F².

The band is held in position also by the edges 46² of the elongated embossment 47², indicated diagrammatically in dotted lines, since the plates 10 D² are not shown in position.

The preferred construction, however, has an integral channel member A, as indicated in Figure 1 and not a two part construction, as shown in Figure 10 with separate channel elements 15 26² for the frame and 29² for the handle.

It is apparent the specific illustrations shown above have been given by way of illustration and not by way of limitation and that the structures above described are subject to wide variation and 20 modification without departing from the scope or intent of the invention, all of which variations and modifications are to be included within the scope of the present invention.

I claim as my invention:—

- 25 1. In a mirror, brush or similar construction, a frame and handle assembly to receive a mirror or brush element comprising a split resilient sheet metal channel rim of U-shaped cross section constituting the periphery and outside edges 30 of the frame and handle, a backing member having an enlarged portion of the same shape and outline as the mirror or brush element, an elongated handle portion, said backing member and said handle portion clamped at their peripheries 35 in the bottom of the U-shaped recess of said channel member and between the flanges of the U of said channel member, said channel member having frame portions embracing said mirror or brush element and substantially parallel handle 40 portions extending along the handle from the base of the frame and forming the exterior sides of said handle and means to draw up said channel, handle and frame portions upon said backing member and mirror or brush element, said means including a tightening metal band slidably mounted upon the outside of said handle at its junction with the frame and embossments upon 45 said handle structure between which said metal band is resiliently mounted in position.
- 50 2. In a mirror, brush or similar construction, a frame and handle assembly to receive a mirror or brush element comprising a split resilient sheet metal channel rim of U-shaped cross section constituting the periphery and outside edges 55 of the frame and handle, a backing member having an enlarged portion of the same shape and outline as the mirror or brush element, an elongated handle portion, said backing member and said handle portion clamped at their peripheries 60 in the bottom of the U-shaped recess of said channel member and between the flanges of the U of said channel member, said channel member having frame portions embracing said mirror or brush element and substantially parallel handle 65 portions extending along the handle from the base of the frame and forming the exterior sides of said handle and a metal band to draw up said channel handle and frame portions upon said backing member and mirror or brush element, said handle including facing plates positioned in said handle on each side of said elongated handle portion, said facing plates having bosses locking 70 said band in position.
- 75 3. In a mirror, brush or similar construction, a frame and handle assembly to receive a mirror or brush element comprising a split resilient sheet metal channel rim of U-shaped cross section constituting the periphery and outside edges 5 of the frame and handle, a backing member having an enlarged portion of the same shape and outline as the mirror or brush element, an elongated handle portion, said backing member and said handle portion clamped at their peripheries 10 in the bottom of the U-shaped recess of said channel member and between the flanges of the U of said channel member, said channel member having frame portions embracing said mirror or brush element and substantially parallel handle 15 portions extending along the handle from the base of the frame and forming the exterior sides of said handle, a metal band drawing up said channel handle and frame portions upon said backing member and mirror or brush element, 20 and means holding said metal band in position at the point of divergence of said parallel handle portions, said channel member being integral and split only at the end of the handle and a clip at the end of the handle holding said split 25 ends together.
4. In a mirror, brush or similar construction, a frame and handle assembly to receive a mirror or brush element comprising a split resilient sheet metal channel rim of U-shaped cross section 30 constituting the periphery and outside edges of the frame and handle, a backing member having an enlarged portion of the same shape and outline as the mirror or brush element, an elongated handle portion, said backing member and said handle portion clamped at their peripheries 35 in the bottom of the U-shaped recess of said channel member and between the flanges of the U of said channel member, said channel member having frame portions embracing said mirror or brush element and substantially parallel handle 40 portions extending along the handle from the base of the frame and forming the exterior sides of said handle and means drawing up said channel, handle and frame portions upon said 45 backing member and mirror or brush element, said means including a tightening metal band slidably mounted upon the outside of said handle at its junction with the frame, said handle including facing plates positioned in said handle on each side of said elongated handle portion, said facing plates having bosses locking 50 said band in position.
5. In a mirror, brush or similar construction, a frame and handle assembly to receive a mirror or brush element comprising a split resilient sheet metal channel rim of U-shaped cross section 55 constituting the periphery and outside edges of the frame and handle, a backing member having an enlarged portion of the same shape and outline as the mirror or brush element, an elongated handle portion, said backing member and said handle portion clamped at their peripheries 60 in the bottom of the U-shaped recess of said channel member and between the flanges of the U of said channel member, said channel member having frame portions embracing said mirror or brush element and substantially parallel handle 65 portions extending along the handle from the base of the frame and forming the exterior sides of said handle and means drawing up said channel, handle and frame portions upon said backing member and mirror or brush element, said means including a stepped tightening band and means 70
- 75

at the top of the handle where said parallel portions hold said band in position receiving and locking the ends of handle and frame channel portions.

- 5 6. In a mirror, brush or similar construction, a frame and handle assembly to receive a mirror or brush element comprising a split resilient sheet metal channel rim of U-shaped cross section constituting the periphery and outside edges of 5
- 10 the frame and handle, a backing member having an enlarged portion of the same shape and outline as the mirror or brush element, an elongated handle portion, said backing member and said handle portion clamped at their peripheries 10
- 15 in the bottom of the U-shaped recess of said channel member and between the flanges of the U of said channel member, said channel member having frame portions embracing said mirror or brush element and substantially parallel handle 15
- 20 portions extending along the handle from the base of the frame and forming the exterior sides of said handle and a metal band drawing up said channel, handle and frame portions upon said backing member and mirror or brush element, said 20
- 25 band being locked into position at the top of the handle, said backing member consisting of a heavy sheet paper material and having a metal reinforcing strap clipped thereto across the junction of the frame and handle portions. 25
- 30 7. In a mirror, brush or similar construction, a frame and handle assembly to receive a mirror or brush element comprising a split resilient sheet metal channel rim of U-shaped cross section constituting the periphery and outside edges 30
- 35 of the frame and handle, a backing member having an enlarged portion of the same shape and outline as the mirror or brush element, an elongated handle portion, said backing member and said handle portion clamped at their peripheries 35
- 40 in the bottom of the U-shaped recess of said channel member and between the flanges of the U of said channel member, said channel member

having frame portions embracing said mirror or brush element and substantially parallel handle portions extending along the handle from the base of the frame and forming the exterior sides of said handle and means drawing up said channel, handle and frame portions upon said backing member and mirror or brush element, said means including a tightening metal band slidably mounted upon the outside of said handle at its junction with the frame, said handle including facing plates positioned in said handle on each side of said elongated handle portion said handle plates and channel member having means locking said band in position at the top of the handle. 15

8. In a mirror, brush or similar construction, a frame and handle assembly to receive a mirror or brush element comprising a split resilient sheet metal channel rim of U-shaped cross section constituting the periphery and outside edges of the 20 frame and handle, a backing member having an enlarged portion of the same shape and outline as the mirror or brush element, an elongated handle portion, said backing member and said handle portion clamped at their peripheries in the bottom of the U shaped recess of said channel member and between the flanges of the U of said channel member, said channel member having frame portions embracing said mirror or brush element and substantially parallel handle portions extending along the handle from the base of the frame and forming the exterior sides of 25 said handle and a tightening band drawing up said channel handle and frame portions upon said backing member and mirror or brush element, said handle including facing plates positioned in said handle on each side of said elongated handle portion, the edges of said handle plates being shouldered so that more central portions of said plates will abut and be flush with 40 the side flanges of said channel member. 35

WILLIAM STEINEN.
